US00D886516S

(12) **United States Design Patent** (10) Patent No.: **US D886,516 S**
 Berresheim (45) Date of Patent: ** Jun. 9, 2020

(54) **BEVERAGE CONTAINER**

(71) Applicant: **GLOBAL ADVANTAGE TRADING AND IMPORTS, LLC**, St. Louis, MO (US)

(72) Inventor: **Kenneth J. Berresheim**, Grantwood Village, MO (US)

(73) Assignee: **GLOBAL ADVANTAGE TRADING AND IMPORTS, LLC**, St. Louis, MO (US)

(**) Term: **15 Years**

(21) Appl. No.: **29/676,263**

(22) Filed: **Jan. 9, 2019**

Related U.S. Application Data

(63) Continuation of application No. 29/596,977, filed on Mar. 13, 2017, now Pat. No. Des. 847,571.

CLAIM

The ornamental design for a beverage container, as shown and described.

DESCRIPTION

FIG. 1 is a side view of a beverage container showing my new design;
FIG. 2 is a top view thereof;
FIG. 3 is a bottom perspective view thereof;

FIG. 4 is a bottom view thereof;
FIG. 5 is a bottom perspective view of a second embodiment of FIG. 1, the only difference being the configuration of the opener, it being understood that all other surfaces are the same as those of the first embodiment;
FIG. 6 is a bottom view of the second embodiment of FIG. 5;
FIG. 7 is a bottom perspective view of a third embodiment of FIG. 1, the only difference being the configuration of the opener, it being understood that all other surfaces are the same as those of the first embodiment;
FIG. 8 is a bottom view of the third embodiment of FIG. 7;
FIG. 9 is a bottom perspective view of a fourth embodiment of FIG. 1, the only difference being the configuration of the opener, it being understood that all other surfaces are the same as those of the first embodiment;
FIG. 10 is a bottom view of the fourth embodiment of FIG. 9;
FIG. 11 is a bottom perspective view of a fifth embodiment of FIG. 1, the only difference being the configuration of the opener, it being understood that all other surfaces are the same as those of the first embodiment;
FIG. 12 is a bottom view of the fifth embodiment of FIG. 11;
FIG. 13 is a bottom perspective view of a sixth embodiment of FIG. 1, the only difference being the configuration of the opener, it being understood that all other surfaces are the same as those of the first embodiment;
FIG. 14 is a bottom view of the sixth embodiment of FIG. 13;
FIG. 15 is a bottom perspective view of a seventh embodiment of FIG. 1, the only difference being the configuration of the opener, it being understood that all other surfaces are the same as those of the first embodiment;
FIG. 16 is a bottom view of the seventh embodiment of FIG. 15;
FIG. 17 is a bottom perspective view of an eighth embodiment of FIG. 1, the only difference being the configuration of the opener, it being understood that all other surfaces are the same as those of the first embodiment;
FIG. 18 is a bottom view of the eighth embodiment of FIG. 17;
FIG. 19 is a bottom perspective view of a ninth embodiment of FIG. 1, the only difference being the configuration of the opener, it being understood that all other surfaces are the same as those of the first embodiment;
FIG. 20 is a bottom view of the ninth embodiment of FIG. 19;
FIG. 21 is a bottom perspective view of a tenth embodiment of FIG. 1, the only difference being the configuration of the opener, it being understood that all other surfaces are the same as those of the first embodiment;
FIG. 22 is a bottom view of the tenth embodiment of FIG. 21;
FIG. 23 is a bottom perspective view of an eleventh embodiment of FIG. 1, the only difference being the configuration of the opener, it being understood that all other surfaces are the same as those of the first embodiment; and,
FIG. 24 is a bottom view of the eleventh embodiment of FIG. 23.
The broken lines in the drawings depict portions of the beverage container that form no part of the claimed design.
